UNITED STATES PATENT OFFICE.

PIERCE OCKENDEN, OF EDMONTON, ALBERTA, CANADA, ASSIGNOR OF ONE-HALF TO
JESSE WARD TREDWAY, OF EDMONTON, ALBERTA, CANADA.

INDEX-CARD HOLDER FOR TELEPHONES.

Application filed October 30, 1924. Serial No. 746,787.

To all whom it may concern:

Be it known that I, PIERCE OCKENDEN, a subject of the King of Great Britain, and residing at the city of Edmonton, in the 5 Province of Alberta, in the Dominion of Canada, have invented new and useful Index-Card Holders for Telephones, of which the following is the specification.

My invention relates to improvements in 10 "index card holders for telephones" and consists of a rod having a forked or U-shaped end, with a set screw through one of the legs with which to clamp the rod to what ever object it is desired to attach to. In this particular instance we have shown the holder attached to a telephone. At the top of the rod is a groove to which is fitted the spring clip holder. The holder is made out of one 15 piece of metal in the form of a T, having the two ends of the top stroke rolled inwards, forming circles, with just sufficient space between them to grip the grooved portion of the rod and hold tightly and at the same time allowing the clip to revolve. The 20 stem of the T is bent backwards and upwards, forming the holder in which is inserted the card which may be of any size or shape required.

When the index card holder is attached 25 to a telephone, the card would contain names and telephone numbers as a handy reference for those requiring to call regularly certain numbers. A small size card can be used and numbers placed on both sides and the 30 spring clip swung around.

This same holder and card system could be used for advertising purposes for window or other displays.

I attain these objects by means of the 35 device as illustrated and more fully described in the accompanying drawings, in which:

Fig. 1 is a perspective view of the holder

attached to a telephone and a card inserted in the clip. 45

Fig. 2 is a front view of the holder showing spring clip attached to upper end of forked rod and clamp screw on lower leg.

Fig. 3 is a side view of the holder.

Fig. 4 is a perspective view of the spring 50 clip.

Fig. 5 is a view of the piece of metal in the T-shape form before being made up into the clip.

Similar figures refer to similar parts 55 throughout the various views.

1 is the forked holder having a clamp screw 2 passing through the lower leg 3. The upper end of the rod of the holder has a groove 4 around its circumference. A 60 spring clip holder 5 is made of one piece of metal cut in T-shape 6, having the ends 7 and 8 rolled in to the centre in circles 9 and 10 and which form the spring clips which grip the grooved portion 4 of holder 1. The 65 lower portion 11 of the T is bent backwards and upwards, forming a holder 12 in which is inserted the card 13 bearing the telephone numbers or other information.

The forked end of the holder 1 fits over 70 the bracket 14 at the back of the mouth piece of the ordinary telephone and is clamped there by the clamp screw 2.

What I claim is:—

The combination of a forked rod with 75 clamp thereto and having one end grooved, a double spring clip fitting within said groove with back in the form of a holder, as and for the purpose specified.

Signed at the city of Edmonton, this 16th 80 day of October, 1924.

PIERCE OCKENDEN.
